US00D373387S

United States Patent [19]

Wu

[11] Patent Number: Des. 373,387

[45] Date of Patent: **Sep. 3, 1996

[54] LIGHT EMITTING DIODE OPEN SIGN

[75] Inventor: Chen-Ho Wu, Los Altos Hills, Calif.

[73] Assignee: Leotek Electronics Corporation,
Taipei, Taiwan

[**] Term: 14 Years

[21] Appl. No.: 45,858

[22] Filed: Oct. 31, 1995

[52] U.S. Cl. D20/10

[57] CLAIM

The ornamental design for a light emitting diode open sign, as described and illustrated.

DESCRIPTION

FIG. 1 is a perspective view of the design of a light emitting diode open sign according to the present invention;

FIG. 2 is a front view thereof;

FIG. 3 is a top view thereof, the bottom view being a mirror image of the top view;

FIG. 4 is a right end view thereof, the left end view being a mirror image thereof; and,

FIG. 5 is a back view thereof.
